UNITED STATES PATENT OFFICE.

ROGER ROSADA, OF GUATEMALA, GUATEMALA.

NON-REFILLABLE BOTTLE.

1,075,066.

Specification of Letters Patent.

Patented Oct. 7, 1913.

Application filed November 30, 1912. Serial No. 734,288.

To all whom it may concern:

Be it known that I, ROGER ROSADA, a subject of the King of Italy, residing at Guatemala city, Guatemala, Central America, have invented new and useful Improvements in Non-Refillable Bottles, of which the following is a specification.

My present invention pertains to bottles that are constructed with a view to pre-
cluding refilling thereof without the fact
being evident; and it consists in the bottle,
hereinafter described and claimed, which
though simple and susceptible of being eco-
nomically manufactured, is highly efficient
for the purpose stated and is also compact
and finished in appearance.

In the accompanying drawings which are
hereby made a part hereof: Figure 1 is a
view, partly in elevation and partly in sec-
tion showing my complete improvement.
Fig. 2 is a diametrical section of the collar
comprised in the improvement. Fig. 3 is
a section on line 3—3 of Fig. 1. Fig. 4 is
a view showing the plug in diametrical sec-
tion and the valve and closure device in
elevation; said view being taken from a
view point at the side of the neck opposite
to that shown in Fig. 1. Fig. 5 is a detail
view of the plug and the spring-pressed fas-
tener, with the plug in the same position as
in Fig. 4.

Similar numerals of reference designate
corresponding parts in all of the views of
the drawings.

The body 1 of the bottle may be of any
shape and construction without affecting my
invention. The bottle neck 2, however, is
peculiar in that it has two opposite and ex-
terior flat sides 3 and in that it has an in-
terior thread 4. From this it follows that
the bottle and neck thereon may be quickly
and easily produced. The neck 2 is also
provided at 5 with an exterior ledge, but
this does not materially increase the cost
of the body and neck.

6 is the collar of my improved bottle
which may be and preferably is of the same
material as the body 1 and neck 2. The said
collar is designed to surround the upper
portion of the neck 2 and rest on the ledge
5, and is also designed to be permanently
affixed to the neck 2 by suitable cement.
Interiorly the lower portion of the collar
6 is provided with opposite flat surfaces 7
which are opposed to the flat surfaces 3
of the neck, and hence effectually prevent
turning of the collar about the neck. It

will also be noted that on its upper edge
the collar 6 is provided with a series of
beveled teeth 8, and that interiorly the col-
lar 6 is further provided with a groove 9,
disposed at the same side of the collar as the
series of teeth 8, and open at its upper end
10 and merging at its lower end in a seat 11.

12 is the cylindrical plug of the novel bot-
tle. The said plug is preferably of celluloid,
though it may be made of any other mate-
rial consonant with its use, without affect-
ing my invention. It is exteriorly threaded
at 13 to engage the interior thread 4 of 70
the neck 2, is provided with an upper plane
portion 14 and a top flange 15, and is verti-
cally grooved at 16 in the plane portion 14.
It will also be understood that the plug 12
is provided with a tortuous passage 17 for 75
the outflow of liquid, and that said passage
17 communicates at its lower end with a
chamber 18 formed in the lower end por-
tion of the plug. In the wall of the cham-
ber 18 are vertical grooves 19 for the pas-
sage of liquid, and at 20 is a gravitating
valve, preferably of hard rubber, disposed
in the chamber 18 and having a rounded
lower end and a toothed upper end, the in-
terdental spaces of said upper end being 80
designed to permit the free passage of
liquid to the passage 17 when the bottle is
inverted or inclined with the neck down-
ward. In order to render it light, the valve
is preferably made with a chamber 21 there-
in, which chamber 21 is open at its upper
end. After the valve 20 is properly placed
in the plug chamber 18, a washer 22 of any
suitable material is connected by cement or
other suitable means to the lower end of 95
the plug 12, which also contributes to the
cheapness of the bottle. The said washer 22
is provided with a central opening 23, the
wall of which is beveled or concaved in
order to form a seat for the valve 20, when 100
the bottle is in upright position with the
neck uppermost. When the bottle is in-
verted or inclined with the neck downward,
the valve 20 gravitates away from its seat,
and then liquid can freely flow through 105
the aperture 23 of washer 22, and then
through the grooves 19 and the interdental
spaces of the valve to the passage 17. At its
upper end the passage 17 is threaded, to
receive a removable threaded plug 24 by 110
which the bottle can be hermetically sealed
when the same is deemed necessary. I do
not, however, confine myself to the use of
the thread mentioned or the plug 24.

Connected at 25 to the under side of the plug flange 15 is a spring strip 26 that is slightly spaced from the said under side, and is provided on its free portion with a 5 detent 27. This latter is designed when the threaded plug is turned in the threaded neck to ride over the teeth 8 of the collar 6, and thereby prevent retrograde movement of the plug until the turning thereof into the neck 10 is completed. Moreover the detent 27 when seated in one of the spaces between teeth 8, is calculated to assist in preventing screwing of the plug 12 out of the neck 2.

Surrounding the plane upper portion 14 15 of the plug 12, and bearing at its upper end against the under side of the flange 15, is a coiled spring 30 which loosely surrounds said plane portion so that its convolutions can move toward and from each other. At 20 its lower end the spring 30 is provided with a catch 31, disposed and movable vertically in and projecting radially from the groove 16 of the plug.

In the practical use of my improved construction, the bottle is filled with liquid 25 through the neck 2, and then the collar 6 is placed on the neck of the bottle, after which the plug 12 is introduced through the collar and is screwed home in the neck. Inci- 30 dental to said operation, the detent 27 serves the purpose stated in combination with the collar teeth 8, while the catch 31 passes down the groove 9 in the collar, and then when the plug is fully inserted and the catch 31 35 has arrived above the seat 11, the spring 30 forces the catch down into the seat 11, and thereby automatically and strongly locks the screw plug in the collar 6 and against withdrawal from the neck 2.

40 The valve 20 and the tortuous character of the passage 17 render it practically impossible to refill the bottle, and to remove said valve 20 and the plug 12, it is first necessary to break the collar 6 which cannot be done 45 without rendering the bottle incomplete and making patent to the most casual observer the fact that the bottle has been refilled.

In the connection just mentioned I would have it understood that when desired, the 50 collar 6 may be formed integral with the bottle neck. In such event when the collar 6 is broken at its weakened point 40, the bottle as a whole is rendered useless. When, however, the construction herein shown is employed, the bottle equipped as described may be used more than once by simply providing a new collar 6 in lieu of the broken one.

Having described my invention, what I claim and desire to secure by Letters-Pat- 60 ent, is:

1. The combination of an interiorly threaded bottle neck, a collar fixed against turning about said neck and extending above

the same and having an interior inclined groove and a seat depending therefrom and 65 also having beveled teeth on its upper edge, an exteriorly threaded plug arranged in and engaging the thread of the neck and having a tortuous passage for liquid, and also having a flange on its upper portion and an up- 70 right groove in its side below said flange, a coiled spring surrounding the upper portion of the plug and bearing against the under side of the flange thereof, a catch carried by said spring and disposed in the said groove 75 of the plug and also disposed in the said seat of the collar, and a spring strip connected with and spaced from the under side of the plug flange and having a detent arranged to ride over and seat between the plug teeth. 80

2. The combination of an interiorly threaded bottle neck, a collar fixed against turning about said neck and extending above the same and having an interior inclined groove and a seat depending therefrom, an 85 exteriorly threaded plug arranged in and engaging the thread of the neck and having a tortuous passage for liquid and also having a flange on its upper side and an upright groove in its side below said flange, a coiled 90 spring surrounding the upper portion of the plug and bearing against the under side of the flange thereof, and a catch carried by said spring and disposed in the said groove 95 of the plug and also disposed in the said seat of the collar.

3. The combination of an interiorly threaded bottle neck having flat portions on its outer side extending downward from its mouth, a collar arranged on said neck and having a weakened portion and interior flattened portions opposed to the said flattened portions of the neck and also having an interior inclined groove and a seat depending therefrom, and further having beveled teeth 100 on its upper edge, an exteriorly threaded plug arranged in and engaging the thread of the neck and having a tortuous passage for liquid, and further having a flange on its upper portion and an upright groove in its 105 side below said flange, a coiled spring surrounding the upper portion of the plug and bearing against the under side of the flange thereof, a catch carried by said spring and disposed in the said groove of the plug and also disposed in the said seat of the collar, and a spring strip connected to the under- 110 side of the plug flange and having a detent adapted to engage the teeth of the neck. 115

In testimony whereof I have hereunto set 120 my hand in presence of two subscribing witnesses.

ROGER ROSADA.
